Patented Nov. 17, 1914.

UNITED STATES PATENT OFFICE.

ARNOLD PFAU, OF MILWAUKEE, WISCONSIN, ASSIGNOR, BY MESNE ASSIGNMENTS,
TO ALLIS-CHALMERS MANUFACTURING COMPANY, A CORPORATION OF DELAWARE.

TURBINE.

1,117,699.

Specification of Letters Patent. Patented Nov. 17, 1914.

Application filed February 20, 1911. Serial No. 699,573.

To all whom it may concern:

Be it known that I, ARNOLD PFAU, a citizen of the Republic of Switzerland, residing at Milwaukee, in the county of Milwaukee and State of Wisconsin, have invented a certain new and useful Improvement in Turbines, of which the following is a specification.

This invention relates to improvements in the construction of turbines and more particularly to means for balancing the runners of turbines.

The object of the invention is to provide a means for balancing the runners of steam, hydraulic, or other fluid pressure turbines, which is simple in construction and efficient in operation.

A clear conception of several embodiments of the invention can be obtained by referring to the accompanying drawing in which like reference characters designate the same or similar parts in different views.

Figure 1 is a transverse vertical section through a hydraulic turbine of the inward flow type. Fig. 2 is an enlarged fragmentary vertical section of the turbine shown in Fig. 1 showing constructive details which have been omitted from the disclosure in Fig. 1. Fig. 3 is a similar view of a modification.

The snail shell casing 1, which receives the water supply from a suitable penstock, not shown, incloses the high pressure chamber 2. Guide ribs 3, which direct the discharge from the high pressure chamber 2 in the usual manner, are directed tangentially toward the turbine runner 7 which is mounted on the main turbine shaft running in bearing 12. An annular series of guide vanes 4, having operating stems 6 projecting laterally therefrom, are mounted to swing intermediate the outer and inner casings 20, 21, of the turbine. The guide vanes 4 are also directed tangentially toward the turbine runner 7. The discharge of the turbine runner 7 is directed toward the draft-tube 9, which draft-tube 9 connects with the tail-race, not shown, in the usual manner.

The main shaft of the turbine is mounted in suitable bearings of which one bearing 12 is shown, and is generally direct connected to an electric or other power generator, not shown. The shaft 8 is an extension of the main shaft and the thrust bearing 13 therefore consists of a thrust member 18 against

which thrust collars 17 formed on the shaft 8, are adapted to bear. The bearing 13 is adjustable longitudinally of the shaft 8 by means of shims 19 inserted between the turbine and bearing casings.

The balancing chamber 11 is formed by the outer casing 20 and the turbine runner 7, and is annular in form. The balancing chamber 10 is formed by the inner turbine casing 21 and the runner 7 and is also annular in form. The two chambers 10, 11, in the illustrated embodiment of the invention, are of equal area in cross section along planes perpendicular to the axis of the main shaft. The annular chamber 14, which is formed by the outer turbine casing 20 and the turbine runner 7, connects with the draft-tube 9 through the pipe 16, the pipe 16 being controllable by a valve 15. The radial cross section of the chamber 14 is exactly equal to the cross section of the discharge opening from the turbine runner 7.

The surfaces on the outer and inner casings 20, 21, between which the guide vanes 4, & coact, see Fig. 2, are lined with suitable rings 27. Wearing rings 28, 29, are fixed to the turbine casings 20, 21, and turbine runner 7, intermediate the chambers 11, 10, and the chamber 14 and draft-tube 9. These wearing rings 28, 29, are of equal diameter and of equal area along adjacent relief surfaces. With the turbine runner 7 inserted within the turbine casings 20, 21, slight annular circumferential spaces 22, 26, exist between the outer periphery of the runner 7 and the inner surface of the rings 27. Annular radial spaces 23, 25, exist between the adjacent surfaces of the rings 28, 29, on either side of the runner 7. The circumferential spaces 22, 26, are of substantially constant axial length as the axial motion of the runner is so small as to have substantially no effect on this length. This smallness of the axial motion of the runner 7 can best be appreciated when it is pointed out that it is less than the mechanical clearance at the thrust bearing and that this mechanical clearance itself is less than the mechanical clearance at the annular spaces 23, 25. In other words, on account of the limited play in the mechanical thrust bearing, the runner 7 is prevented from rubbing at annular spaces 23, 25; and as soon as the balancing fluid pressures are active, the revolving parts will even be prevented thereby from 110

rubbing at the mechanical thrust bearing. This results in the revolving parts having an exceedingly small end play.

Suitable mechanism for operating the 5 guide vanes 4 is attached to the outer ends of the operating stems 6 of the vanes 4. The operating ring 5 is connected to this mechanism and serves to adjust the vanes 4 to any desired position. The details of the 10 operating mechanism for the guide vanes 4 have been omitted from the present disclosure since they form no part of the present invention and are well known in the art.

Referring to the modification, see Fig. 3, 15 the turbine runner 70 is inclosed within the outer and inner casings 200, 210. A series of balancing chambers 100, 101, are formed between the inner casing 210 and the runner 70, while a second series of balancing chambers 20, 110, 111, exist between the outer casing 200 and the runner 70. Constant sized, annular, restricted passages 220, 260, exist between the outer periphery of the runner 70 and the inner cylindrical surface of the ring 25 27. Automatically variable-sized, annular radial passages 230, 250, exist between side surfaces of the runner 70 and casings 210, 200, respectively, and form means for discharging pressure from the inner chambers 30 101, 111, respectively. The annular, radial passages or spaces 122, 121, which exist between side surfaces of the runner 70 and casings 210, 200, respectively, form automatically variable means of pressure communication between the chambers 100, 101, on one side and chambers 110, 111, on the opposite side of the runner 70.

During the operation of the turbine, the 40 fluid under pressure which at such time exists within the chamber 2, is admitted to the turbine runner 7 through passages between the guide ribs 3 and guide vanes 4, and after being relieved of its energy in the runner 7, is discharged to the draft-tube 9 from 45 whence it flows to the tail-race. As the working fluid passes the annular spaces 22, 26, owing to the high pressure thereof, a portion flows into the annular balancing chambers 10, 11, formed intermediate the 50 casings 21, 20, and the turbine runner 7. The chamber 14 being connected through the pipe 16 to the draft-tube 9, has established therein a pressure equal to that within the draft-tube 9. This pressure may be considerably below atmospheric. It will be noted 55 that with this arrangement, and in the specific embodiment illustrated, on account of the equal effective areas of the balancing chambers 10, 11, as well as the equal effective 60 areas exposed to the draft-tube pressure, the turbine runner 7 is exposed to exactly equal pressures on either side thereof. If the predetermined effective areas of the balancing chambers 10, 11, are unequal, the fluid pressure 65 must also be unequal but inversely so in

order to equalize the total fluid pressures on opposite sides of the runner 7. These total fluid pressures must be equal in all cases where there is no additional force on the runner to be considered, such as weight of 70 revolving parts in a vertical machine. In such case these total fluid pressures are unequal only to the extent of the additional force on the runner 7. If, however, for any reason an additional thrust should be thrown 75 upon the runner 7 at one side thereof, thus unbalancing the total end forces on the runner, one of the annular radial spaces 23, 25, will be diminished. Because the annular inlet spaces 22, 26, remain of constant cross 80 section and substantially constant length, this will cause less high pressure fluid to pass through the choked radial space and build up pressure within that one of the corresponding balancing chambers 10, 11, on 85 the side of the restricted passage. More specifically, suppose the runner 7 to be forced to the left by an additional thrust. The annular radial space 25 would then be decreased in width and the fluid flowing into 90 the balancing chamber 11 through the circumferential annular chamber 26 would build up the pressure within the chamber 11. As the runner 7 moves toward the left, the annular radial space 23 formed between the 95 turbine casing 21 and the turbine runner 7 increases in width, thereby relieving somewhat the pressure within the balancing chamber 10. This building up of the pressure within the chamber 11 places a thrust 100 upon the left face of the runner 7 to bring same back to normal position by balancing the additional thrust which primarily caused the shifting of the runner 7 to the left.

It will be seen that if for any reason 105 the runner 7 is forced toward the right, the operation of the balancing device will be similar, the annular space 25 in this case increasing and causing the pressure within the balancing chamber 10 to build up while 110 that within the balancing chamber 11 is diminished.

The bearing 13 and thrust members 18 are so adjusted by means of the shims 19 as to permit contact of the thrust collar 17 115 with the thrust members 18 only during starting of the turbine and before pressure has been established within the balancing chambers 10, 11. After the turbine is running normally, the thrust collar 17 will be 120 free from coaction with the thrust members 18, the thrust being automatically balanced by the variations in pressure within the balancing chambers 10, 11. By inserting wearing rings 28, 29, between adjacent members, the adjacent surfaces can 125 be perfectly formed free from blow-holes or other defects peculiar to cast metal. By forming the rings 28, 29, separate from the main casings, easy means is provided for 130

replacing members subject to wear from erosion.

It should be understood that it is not desired to be limited to the exact details of 5 construction shown and described, for obvious modifications will occur to a person skilled in the art.

It is claimed and desired to secure by Letters Patent,—

10 1. In combination, a casing, a runner within said casing, a pressure chamber at one side of said runner, means of pressure communication to said chamber, said means being of constant cross-section and substantially constant length, means of pressure discharge from said chamber, said means comprising spaced opposed relief surfaces of said runner and casing, and balancing means on the opposite side of 15 said runner for urging same in one direction only.

20 2. In combination, a casing, a runner within said casing, pressure chambers on opposite sides of said runner, means of pressure communication to said chambers, said means being of constant cross-section and substantially constant length, and means of pressure discharge from said chambers, said means comprising spaced opposed relief surfaces of said runner and casing.

25 3. In combination, a casing, a runner within said casing, a series of balancing pressure chambers at one side of said runner, means of pressure communication to said series of chambers, said means being of constant cross-section and substantially

constant length, means of pressure discharge from said series of chambers and of pressure communication between the chambers of said series, said means of discharge and 40 of communication each comprising spaced opposed relief surfaces of said runner and casing, and means for subjecting said runner to a counter-balancing pressure.

4. In combination, a casing, a runner 45 within said casing, a series of balancing pressure chambers on opposite sides of said runner, means of pressure communication to each of said series of chambers, said means being of constant cross-section and substantially constant length, and means of pressure discharge from each of said series and of pressure communication between the chambers of each of said series, said means of discharge and of communication each 50 comprising spaced opposed relief surfaces of said runner and casing.

5. In combination, a casing, a runner within said casing, a pressure chamber at each side of said runner, said chambers having annular inlet spaces of constant cross-sectional area and substantially constant length and located between cylindrical surfaces of said runner and casing, and said chambers having annular outlet spaces of 65 variable cross-sectional area.

In testimony whereof, I affix my signature in the presence of two witnesses.

ARNOLD PFAU.
